UNITED STATES PATENT OFFICE

MARTIN LIPPE, OF CHICAGO, ILLINOIS, ASSIGNOR TO HEDMAN MANUFACTURING COMPANY, OF CHICAGO, ILLINOIS, A CORPORATION OF ILLINOIS

COIN-DELIVERY CHUTE

Original application filed June 6, 1924, Serial No. 718,212. Divided and this application filed July 23, 1927. Serial No. 207,830.

My invention relates to change making machines in general and more particularly to means for conveying coins from the machine to a receptacle.

5 It is an object of my invention to provide a discharge and delivery means for coin changing and similar machines which is practical in construction, reliable and rapid in operation, may be conveniently used and which may be economically manufactured.

10 Other objects will appear from the following description, reference being had to the accompanying drawings, in which

15 Fig. 1 is a front sectional view of the machine, omitting the majority of the action elements of the operating mechanism in the lower part of the machine and showing the interior coin discharging chute of the machine in longitudinal section;

20 Fig. 2 is a plan view of a portion of the left-hand side of the machine with the coin delivery means extending therefrom;

Fig. 3 is a sectional elevation of said coin delivery means;

25 Figs. 4, 5 and 6 are cross sections of the coin delivery chute taken, respectively, on the lines 4—4, 5—5 and 6—6 of Fig. 2.

This application is a division of my co-pending application, Serial No. 718,212, filed 30 June 6, 1924, (Patent No. 1,673,366, granted June 12, 1928) in which the coin tray and other mechanism is specifically claimed.

The illustrative machine is equipped with a removable coin tray 1, comprising a row of 35 coin magazines 2, one for each denomination of coin to be ejected. This tray, appearing at the upper front of the machine, is mounted in operative relation to a set of devices 3 for removing or ejecting coins from the magazine.

The coin ejectors 3 may be operated by appropriate mechanism, such for example as that shown in the drawings, which is of the general type disclosed in the patent to Barrett,

45 No. 1,247,618, dated November 27, 1917.

The coins discharged or ejected from the magazines drop upon and ride down an inclined coin slide 40, and are discharged through an opening 41 in one of the side

terior delivery chute 50. Said inclined coin slide 40 constitutes the bottom of an interior discharge chute or receptacle 42, the front wall of which is provided by the front wall of the machine casing. The coin slide 40 is advantageously made as a separate sheet metal strip, fitted and secured between the front and back walls of the interior chute or receptacle 42.

The coin magazines are preferably arranged with the larger coins to the right (Fig. 1). This arrangement is advantageous because the heavier coins, dropping upon the elevated end of the coin slide 40, will slide down the same and out through the opening 41 at nearly the same time as the lighter coins drop upon the lower end of the slide; while the lighter coins, having the furthest distance to drop, will thereby acquire such a momentum in proportion to size by the time 70 they strike the slide as to cause them to travel down the slide and the extension or delivery chute 50 practically or nearly concurrently with the heavier coins.

To promote reliable and speedy delivery 75 of the coins, the coin-slide 40 is formed with a longitudinal channel 46 flanked by shoulders 47, the arrangement being such that the coins can have only two-point contact with the slide no matter what may be the relation 80 of the coins as they ride down the slide; the width of the channel and of the shoulders 47 or the distances between the channel and sides of the interior chute being less than the diameter of the smallest coins. By the 85 provision of this channel or trough 46 the coins slide with only two points in contact with the chute, thus minimizing the friction, especially if the chute's surface is damp, corroded or has accumulated dust. This arrangement thus promotes speedy delivery of the coins and overcomes the tendency of the coins to be retarded or stopped by the effect 90 of dust accumulation, rust or the like.

The exterior delivery chute 50, forming a 95 continuation of the interior chute, is shown inclined downwardly and curved laterally toward the back of the machine for delivering the coins to a position convenient to the customer or recipient of the change (Figs. 1, 100

2 and 3). At the delivery end of the chute is a barrier 51 to arrest the travel of the coins and cause them to drop through the opening 52. The chute is shown as of substantial 5 right-angular cross section, with the bottom thereof of the same form and character as the interior coin slide 40, said bottom of the chute 50 being formed with the channel 53 flanked by the shoulders 54 (Figs. 4, 5 and 6). This 10 formation, enabling the coins to ride down the chute 50 on two-point bearings, minimizes friction and the retarding effect of dust, corrosion or the like, thus promoting speedy delivery as already explained. On the other 15 hand, the gradual deflection of the travel of the coins incident to the curvature of the chute 50 exerts a desirable retarding influence. Furthermore, the inclination of the chute decreases toward its delivery end, as appears 20 more clearly in Fig. 3, tending to check the velocity of the coins. By the time the coins reach the delivery end of the chute, they will be moving in such manner and at such rate as to insure dropping through the opening 52 25 or striking against the barrier 51 and dropping into said opening without over-shooting or undesirable rebounding.

The coins are deposited in a cup 55. The bowl of this cup may be pear-shaped in plan 30 view, as shown in Fig. 2, and semi-pear-shaped in longitudinal section, as shown in Fig. 3. This formation provides a main cup portion or concavity 56 with a tapering chute-like extension 57, having an inclined bottom merging into the bottom of the deeper portion or main concavity 55 of the cup. The cup is disposed with its chute-like extension 57 under the discharge opening 52 in the delivery end of the chute 50, there being only a 35 slight distance between said opening and the bottom of said cup extension 57, so that the coins delivered by the chute 50 have a short drop into the cup. The said cup extension 57 serves as an auxiliary chute down which the 40 coins slide into the main deeper portion or recess 56 of the cup, from which they may be conveniently removed by the customer or recipient of the change delivered from the machine, said deeper portion of the cup being 45 shaped to permit picking up the assembled coins by the fingers.

The travel of the coins ejected from the magazines of the machine by the change-making operation may be considered as comprising three steps, a high-speed step on the coin slide 40, a second step in the extension chute 50 at relatively high-speed until the coin is arrested by the coin barrier 51 at the delivery end of the chute, and then a relatively slow speed of travel from the rear 55 higher end to the front deeper end of the cup to effect the depositing of the coins in the ultimate terminus without danger of throwing them out.

60 65 The cup 55 is shown formed integrally with

a peripheral wall 58 having ears 59 by which the cup is attached to a sheet metal base plate 60, the latter being attached to the bottom plate 61 of the machine casing as indicated at 62 in Figs. 2 and 3. The coin chute 50 may be formed as a sheet metal stamping having its inlet end formed with a flange 63 for attachment to the side wall 64 of the machine casing by screws 65 or the like as shown in Figs. 1 and 2.

The several improvements described promote reliability of operation in the delivery of successive batches of change to customers during more or less frequent repeated operations of the machine; contribute to the production of a machine of convenient character; and provide a practicable structure susceptible of economical manufacture.

Obviously the present invention is not limited to the precise details of construction, form and arrangement of the illustrative machine, since the same may be variously modified in accordance with the character, organization and requirements of different machines. Moreover it is not indispensable that all of the features of the invention be used conjointly since they may be advantageously used in various different combinations and subcombinations.

Having thus described my invention, I 95 claim:

1. In a machine of the class described, an interior coin chute arranged to effect a rapid and substantially concurrent discharge of coins of different denominations simultaneously placed upon different portions thereof, said chute being formed with a pair of longitudinally extending shoulders to provide a two-point contact with the coins as they slide down the chute, and having a downwardly inclined curved extension portion having at its delivery end an integral barrier and opening in front of said barrier into which the coins may drop.

2. In a machine of the class described, a chute for the rapid delivery of coins from a coin-ejecting mechanism, said chute comprising a steep downwardly inclined portion, and a portion of lesser downward inclination, each of said portions being channel-shaped in cross section and having a trough with inclined sides formed in the bottom of said channel.

3. In a machine of the class described, a chute for the rapid delivery of coins from a coin-ejecting mechanism to a receptacle, said chute comprising a downwardly inclined continuous channel-shaped trough having a depressed portion extending longitudinally thereof, the width of the bottom of the depressed portion being less than the diameter of the smallest coin adapted to be conveyed by the chute, whereby the coins will contact at two points only in sliding down the chute.

4. In a device of the class described, a chute

for the delivery of coins, comprising an upper rectilinear portion of relatively steep slope, and a lower arcuate portion of lesser slope, each of said portions being substantially 5 U-shaped in cross section and having longitudinally extending shoulders at each side of their bottom surfaces.

In witness whereof, I hereunto subscribe my name this 19th day of July, 1927.

MARTIN LIPPE.
